UNITED STATES PATENT OFFICE.

GEORGE W. LEE, OF BINGHAMTON, NEW YORK.

METHOD OF AND APPARATUS FOR MANUFACTURING HEADED PINS, &c.

SPECIFICATION forming part of Letters Patent No. 621,832, dated March 28, 1899.

Application filed October 7, 1898. Serial No. 692,889. (No model.)

To all whom it may concern:

Be it known that I, GEORGE W. LEE, a citizen of the United States, and a resident of Binghamton, in the county of Broome and 5 State of New York, have invented a new and useful Improvement in the Method of and Apparatus for Manufacturing Headed Pins for Screws, Rivets, and the Like, of which the following is a specification.

10 My invention relates to an improvement in the method of and apparatus for forming headed pins from blanks of metal, the said pins being intended for use as rivets, screws, and the like.

15 One object of my invention is to provide an improvement in the method of manufacturing headed pins in which the metal which forms the blank is displaced in a direction perpendicular to the face thereof to form a 20 pin to which the surrounding portion of the blank forms the head.

A further object is to provide means for carrying out this method.

25 A further object is to provide an apparatus for forming headed pins in which means are provided for determining the length of the pin and in which means are provided for ejecting the headed pin from the machine after it has been formed from the blank.

30 A further object is to provide means whereby headed pins may be formed with heads of much larger diameter, if so desired, than has hitherto been possible by the well-known method of forming the headed pins from wire.

35 In the accompanying drawings, Figure 1 represents a face view of a blank of disk form. Fig. 2 represents an edge view of the same. Fig. 3 represents a top plan view of the headed pin. Fig. 4 is a side view of the 40 same. Fig. 5 represents a side view of a headed pin with the pin portion threaded to form a screw. Fig. 6 is a view, partially in vertical central section, of a press for forming the headed pins, a blank being shown

45 within the seat in the platen of the press and the plunger being represented as being raised away therefrom. Fig. 7 is a detail vertical central sectional view showing the plunger depressed and the headed pin formed; and

50 Fig. 8 represents a detail vertical central sectional view with the plunger raised and the

ejector raised, indicating the manner of removing the headed pin from the platen.

The table or bed-plate of the press is denoted by A, its uprising yoke by a, and its 55 legs by a'. A platen B is inserted in the bed-plate A, and a vertically-reciprocating plunger C is mounted in the uprising yoke a, which plunger is provided with a suitable operating means, which in the present instance consists of a cam D, carried by the yoke and provided with a suitable handle d.

The platen B extends vertically through the bed-plate A of the press and may be removed therefrom when it is desired to replace 65 it by another platen. The platen B is provided with a shallow seat b, which is of such shape and size that it will engage the periphery of the blank E, from which the headed pin is to be formed. The said seat in the 70 present instance is of circular form, and the blank is a disk.

The platen B is provided with a screw-threaded socket b' of considerable diameter, leading from its bottom upwardly a considerable distance toward its top. A vertical hole b² leads downwardly from the center of the seat b into the screw-threaded socket b'. This hole b² is made of the diameter which it is desired to have the pin which is to be 80 formed from the blank E.

The plunger C consists of an upper section c and a lower section c', having a screw-threaded engagement with the upper section. A lock-nut c² has a screw-threaded engagement with the lower portion c' of the plunger and serves to lock the said lower portion in any desired adjustment. The bottom face of the lower portion c' of the plunger is shaped so as to enter the seat b of the platen B and snugly 90 fit within the walls of the seat, so that when the proper amount of pressure is brought to bear upon the said plunger a portion of the metal of the blank E within the seat is caused to flow downwardly into the hole b² without 95 permitting the blank to extend laterally. The depth of the hole b² from the seat downwardly may be adjusted so as to regulate the length of the pin portion of the headed pin by means of a vertically-disposed rod F. This 100 rod F is provided with a collar f within the recess b', and the portion of the rod below

the said collar extends through an adjusting plug G, which has a screw-threaded engagement with the recess b'. As this plug G is screwed upwardly the rod F is thereby forced upwardly in the hole b² toward the seat b. A spring f' extends between the collar f and the upper end of the recess b', tending to keep the rod F at all times at the limit of its downward movement. A lock-nut g engages the screw-threaded portion of the plug G and serves to lock the plug in any required adjustment.

After the headed pin has been formed it may be ejected from the platen by the following means: A rock-lever H is pivoted to a bracket h, depending from the bed-plate A of the press, and one arm h' of the rocking lever is caused to engage the lower portion of the rod F, so that when the other arm h² of the rocking lever is depressed the lower portion of the rod F will be forced upwardly through the plug G and the upper portion of the said rod will be forced upwardly through the hole b², thereby lifting the headed pin out of the platen.

It is to be understood that the upper end of the rod F may be made of any desired shape, so as to produce a rounded, pointed, flat, or other shape to the end of the pin portion of the headed pin. It is also to be understood that the platens may be provided with seats b of any desired shape and size to form different styles of heads for the headed pins and that the holes b², leading from the seats, may be made of different diameters to form different sizes of pins.

The pin portion of the headed pin may be screw-threaded, as shown in Fig. 5, to form a screw, or it may be used plain—as, for instance, as a rivet.

When the blank is compressed to cause the metal therefrom to flow down into and fill up the hole b², an irregular depression would be left upon the upper face of the blank over

the said hole if the bottom face of the plunger C were left perfectly plain. To produce a more finished looking top face to the head, I provide the bottom face of the plunger with a slight seat or projection c³, directly over the hole b².

While I have shown a hand-press in the accompanying drawings, I wish it understood that this form of press was simply used as an illustration to show a means for operating the plunger, it probably being preferable to use a power-press in general practice, because of the greater amount of pressure which could be obtained by the use of such power-press.

It is evident that slight changes might be resorted to in the form and arrangement of the several parts without departing from the spirit and scope of my invention. Hence I do not wish to limit myself strictly to the structure herein set forth; but

What I claim is—

1. The herein-described method of shaping cold metal consisting in forcing the metal composing the blank to flow inwardly in a direction away from the periphery and thence directing it laterally away from the blank, substantially as set forth.

2. Means for confining a piece of metal edge-wise to prevent its expansion, a support for the piece of metal provided with a hole leading away from the face of the support and means for exerting pressure upon the face of the piece of metal and for directing the metal into the hole to form a pin integral with the metal.

In testimony that I claim the foregoing as my invention I have signed my name, in presence of two witnesses, this 27th day of September, 1898.

GEORGE W. LEE.
